UNITED STATES PATENT OFFICE.

JEFFERSON S. PALMER, OF FARMINGTON, NEW MEXICO.

DEVICE FOR ELIMINATING STATIC CURRENT AND FOR TUNING RADIO RECEIVING SETS.

Application filed October 15, 1924. Serial No. 743,719.

This invention relates to devices for use in connection with radio receiving sets, particularly for tuning the input circuit of said receiving set, and for eliminating static interference therein.

An object of the invention resides in providing a device adapted for connection in the circuit between the antenna and the receiving set, as well as the ground and the receiving set, which includes a pair of relatively adjustable elements, adapted for tuning the input circuit, and another pair of elements relatively adjustable, and having an inductive relation with one another, so that static current may be induced to flow between the last mentioned elements, in order that they may be conducted from the antenna circuit to the ground circuit, without passing through the radio receiving set, and which thereby eliminates said static current from the set.

Another object of the invention resides in providing a spider web inductance having one free end connected with the antenna, and with which is associated a movable plate member adapted for adjustment axially relative to said spider web inductance, and which supports in spaced relation thereto a movable inductance coil arranged in the magnetic field of an electromagnet, the inductance coil being electrically connected with the plate, and one side of the input circuit of a receiving set, so that in the antenna circuit the current flows from the antenna through the spider web inductance and then to the plate, and movable inductance coil before entering the set, while the ground circuit of said receiving set is through a variable condenser and the electromagnet, before reaching the ground, from which it will be understood that static current will be conducted directly from the antenna to the ground, by the inductive relation of the movable inductance coil, and the electromagnet, in order that such currents, which set up undesirable noises in the receiving set may be eliminated.

The invention also includes other objects and improvements in the details of construction and arrangement of parts for carrying out the invention, which are more particularly pointed out in the following detailed description, and in the claims directed to a preferred form of the invention, it being understood, however, that various changes in the minor details and manner of construction

may be made, without departing from the spirit and scope of the invention as described and claimed.

The figure illustrates a partial diagrammatic and structural view of the improved device, showing the wiring connections with the input circuit of the radio set, together with the ground and antenna connections, the supports for the several elements of the device being omitted for the sake of clearness.

1 indicates an inductance, preferably in spider web form, and of any well known type now used in the art, one end of which is connected by a wire 2 to the antenna 3 of the radio receiving set. The spider web inductance is preferably mounted in a vertical plane as illustrated in the drawing, and associated with which is a movable cylindrical plate member 4 of substantially the same size as the spider web inductance, and which is movable axially relative to said inductance. A pair of rods 5 attached to opposite sides of the plate member connect the same with the supporting member 6 of a primary inductance coil 7, having the windings 8 wound on said supporting member, one end of said winding being connected by a wire 9 to one of the rods 5 establishing electrical connection between the coil 8 and plate member 4. A rack bar 10 is mounted on said plate 4 and the teeth 11 thereon engage the toothed periphery of a pinion 12, mounted on the shaft 13 and adapted to be manually rotated through the operation of the knob 14, in order that the disc 4 and the inductance coil 7 may be moved for changing the relative position of the plate 4 with respect to the spider web inductance 1 and the position of the movable inductance coil 7 with respect to the stationary electromagnet 15.

The stationary electromagnet includes a laminated core 16 and coil winding 17, one end of the coil winding and the core being electrically connected to the ground 18 through wire connections 19. The wire connection 20 electrically connects the opposite end of the core 16 with the connection 19 so that both ends of the core 16 are grounded. The other end of the coil winding 17 of the stationary electromagnet is connected to a variable condenser 21 through a wire connection 22, while the variable condenser is connected to one side of the input circuit of a radio receiving set, the

through a wire connection 23, while the magnet mounted in spaced relation to said other terminal 24 of the radio receiving set is connected to the free end of the coil windings 8 of the movable inductance coil, 5 through a wire connection 25, in which is interposed a controlling switch 26.

The bar member 27 carries an adjustable screw member 28, which is arranged to adjust the air gap with the upturned end 29 10 of the parallel bar member 30 arranged in parallel spaced relation to the bar member 27, which bar members are electrically connected by wire members 31 and 32 respectively, with the wires 19 and 25 respectively, so 15 that a by-pass circuit containing an adjustable air gap having a predetermined resistance is connected across the antenna ground circuit for diverting the static to the ground.

With the parts connected as above described, 20 it will be seen that the operation of the knob or handle 14 will effect an adjustment of the movable inductance coil 7 and the plate 4 relative to the stationary magnet and the spider web inductance 1, which will 25 effect a tuning of the input circuit of the receiving set according to the spacing of the plate 4, relative to the spider web inductance 1. At the same time, the relative adjustment of the movable inductance coil with 30 respect to the stationary electromagnet will effect the inductive relation between said magnet and inductance coil, in such a manner that static electricity and undesirable received currents will be transmitted by induction to the core 16 of the electromagnet and then to the ground, and not into the 35 input circuit of the receiving set.

It will thus be seen that a novel and simple device has been provided for eliminating 40 static interference in the input circuit of a radio receiving set, and at the same time providing an additional tuning device for tuning an incoming signal.

What is claimed is:

45 1. A device of the class described comprising a stationary inductance coil, a plate movably mounted in the magnetic field of said inductance coil, a stationary electro-

magnet mounted in spaced relation to said inductance, a movable inductance coil 50 mounted in spaced relation to said plate and in inductive relation to the electromagnet, and connections for interposing the stationary inductance coil, plate, and movable inductance coil in the circuit between the antenna and the input circuit of a radio receiving set, and for interposing the electromagnet in the circuit connecting said receiving set with the ground.

2. A device of the class described comprising 60 a stationary inductance coil, a plate mounted in the field of said coil and axially movable therein, a movable inductance coil connected with said plate and arranged in spaced relation thereto, a stationary electromagnet mounted adjacent said movable inductance coil and arranged in inductive relation thereto, means for adjusting said plate and movable inductance coil, and connections for interposing the stationary inductance coil, the plate, and the movable inductance coil in the circuit between the antenna and one side of the input circuit of the radio receiving set, and connections between the other side of the input circuit and the 70 radio receiving set and the ground, for interposing the stationary electromagnet in said circuit.

3. A device of the class described comprising 80 a stationary inductance coil connected with an antenna, a stationary electromagnet connected between the ground and one side of the input circuit of a radio receiving set, and means arranged in inductive relation with said stationary inductance 85 coil and said electromagnet, electrically connected with the other side of the input circuit of said receiving set, and relatively adjustable to said stationary coil, said electromagnet tuning said input circuit of the radio receiving set, and forming an inductive circuit for predetermined currents between the antenna and ground.

In testimony whereof I affix my signature.

JEFFERSON S. PALMER.
